UNITED STATES PATENT OFFICE.

HÉLÈNE SILBERFELD, OF NEW YORK, N. Y.

DESIGN FOR A DOLL.

Application filed November 17, 1922. Serial No. 4,321. Term of patent 3½ years.

To all whom it may concern:

Be it known that I, HÉLÈNE SILBERFELD, a subject of the Kingdom of Belgium, residing at New York city, in the county of New York and State of New York, have invented a new, original, and ornamental Design for Dolls, of which the following is a specification, reference being had to the accompanying drawing, forming part thereof, and in which—

Fig. 1 is a front perspective view of a doll, showing the new design, and Fig. 2 is a side view thereof.

I claim:

The ornamental design for a doll, substantially as shown.

HÉLÈNE SILBERFELD.
